Patented Sept. 17, 1963

196,320

COMBINED WEIGHING AND COMPUTING MACHINE FOR AIRLINE BAGGAGE OR SIMILAR ARTICLE

Albert Hohmann, Brooklyn, N.Y., assignor to American Electronics, Inc., Fullerton, Calif., a corporation of California

Filed Sept. 25, 1961, Ser. No. 66,839

Term of patent 14 years

(Cl. D52—10)

FIG. 1

FIG. 2

FIG. 3

FIG. 4

FIGURE 1 is a plan view of a combined weighing and computing machine for airline baggage, showing my new design.

FIGURE 2 is a front elevation thereof.

FIGURE 3 is a side elevation taken from the right of FIGURE 2.

FIGURE 4 is a side elevation taken from the left of FIGURE 2.

The rear of the machine is substantially plain and unornamented.

The essential features of the design reside in the portions shown in full lines.

I claim:

The ornamental design for a combined weighing and

computing machine for airline baggage or similar article, substantially as shown and described.
